CLAIM

The ornamental design for a portion of a slab, as shown and described.

DESCRIPTION

The patent or application file contains at least one drawing executed in color. Copies of this patent or patent application publication with color drawing(s) will be provided by the Office upon request and payment of the necessary fee.

The sole FIGURE is a top plan view of a portion of a slab, showing our new design. The surface of the portion of the slab is flat.

The slab is suitable for use in living or working spaces (e.g., along a countertop, table, floor, or the like).
